(57) **CLAIM**

The ornamental design for a front face of a steering wheel, as shown and described.

DESCRIPTION

FIG. 1 is a front elevational view of a front face of a steering wheel showing my new design; and,

FIG. 2 is a front elevational view of a second embodiment of a front face of a steering wheel showing my new design.

The broken line showings of a logo in FIGS. 1-2 and of the circular buttons and adjacent controls in FIG. 2 are for illustrative purposes only and form no part of the claimed design.

1 Claim, 2 Drawing Sheets

FIG. 1

FIG. 2
